LAMP BASE

Clarence J. Cottrell, 868 Park Ave., Baltimore, Md.

Filed Feb. 24, 1960, Ser. No. 59,499

Term of patent 14 years

(Cl. D48—20)

Fig. 1.

Fig. 2.

The dominant features of my design reside in the portions shown in the full lines.

I claim:

The ornamental design for a lamp base, as shown and described.
